UNITED STATES PATENT OFFICE.

JOHN S. BOSWELL, OF FORT WORTH, TEXAS, ASSIGNOR TO SOUTHERN FRUIT JULEP COMPANY, OF FORT WORTH, TEXAS.

DESIGN FOR A TUMBLER.

Application filed December 27, 1923. Serial No. 8,163. Term of patent 3½ years.

To all whom it may concern:

Be it known that I, JOHN S. BOSWELL, a citizen of the United States, residing at Fort Worth, in the county of Tarrant and State of Texas, have invented a new, original, and ornamental Design for Tumbler, reference being had to the accompanying drawing, forming part thereof.

I claim:

The ornamental design for a tumbler, as of which the following is a specification, shown.

JOHN S. BOSWELL.
